UNITED STATES PATENT OFFICE.

ALFRED COPONY, OF CHICAGO, ILLINOIS, ASSIGNOR OF ONE-HALF TO CHARLES R. COOPER, OF CHICAGO, ILLINOIS.

DRAFT-RIGGING FOR RAILWAY-CARS.

1,253,790.

Specification of Letters Patent. Patented Jan. 15, 1918.

Application filed September 10, 1915. Serial No. 48,971.

To all whom it may concern:

Be it known that I, ALFRED COPONY, a subject to the Emperor of Austria, residing at Chicago, in the county of Cook and State 5 of Illinois, have invented new and useful Improvements in Draft-Rigging for Railway-Cars, of which the following is a full, clear, concise, and exact description, reference being had to the accompanying drawing, forming a part of this specification.

My invention relates to draft rigging for railway cars, and more specifically to the spring pocket and associated mechanism of such draft rigging.

Among the objects of my invention is to provide a draft rigging which will be simple in construction, efficient in use and easy to manufacture and assemble.

In the drawings, in which I have shown 20 one embodiment of my invention,

Figure 1 is a plan view of my improved draft rigging;

Fig. 2 is a vertical section on the line 2—2 of Fig. 1;

Fig. 3 is a vertical section on the line 25 3—3 of Fig. 1;

Fig. 4 is a side elevation of one of the guide and abutment members; and

Fig. 5 is a side elevation of the loops or 30 links which embrace the shock absorbing means.

Referring now to the drawings in detail I have shown my invention in connection with the draft sills 10 of a car to each of 35 which is secured a cheek-plate forming a guide and abutment member 11, a pair of loops or links 12 and 13 of any suitable material as cast steel located between the sills 10 and held in place and guided in the 40 members 11, a pair of followers 14 capable of engagement with the members 11 and between which the springs 15 are held in place, a retaining member 15^a located between the two sets of springs to hold them 45 separate and prevent their interfering with each other, a draw bar 16 connected with the loops 12 and 13 and a tie-plate 17 secured to the sills 10 and located beneath the springs 15 for holding the latter in position.

The abutment members 11 are similar in 50 all respects and a description of one will be sufficient. Each comprises upper and lower abutments 19 for taking care of a pull on the draw bar, upper and lower abutments 55 20 for taking care of the strain due to the

cars being jammed together, and guide-ways or channels 20^a for holding the loops 12 and 13 in place and guiding them in their movement. The loops 12 and 13 are also similar and each comprises an abutment portion 21 60 for engagement with one of the followers 14, a pair of side bars 22 located within the guide-ways 20^a, an abutment portion 23 for engagement with the head of the draw bar 16, and spaced guiding and retaining walls 65 24 which, together with the abutment portion 23, forms a passage through which the draw bar 16 extends.

Each of the followers 14 comprises a pair of lugs 25 which extend within the coils of 70 the springs 15 to hold the latter in position. The springs 15 may be of any suitable construction, and, as shown, comprise inner and outer coil springs 26 and 27 located between the followers 14 and held in place thereby. 75 The retaining member 15^a is located between the two sets of springs and is formed with curved spring engaging portions 28 and 29 to assist in holding the springs in their proper relative position. The draw bar 16 80 is provided with the usual coupling head 30 and the usual T-shaped head 31 for engagement with the loops of the spring pocket. The tie-plate 17 is provided with a curved portion 32 for holding the springs 15 in 85 position and preventing them from dropping out, and is secured to the sills 10 in any suitable manner as by bolts 33.

In assembling the draft rigging the loops 12 and 13 are first placed in proper relative 90 position with respect to the head of the draw bar 16 with the draw bar extending out through the passage formed by the portions 23 and 24. With these parts thus assembled the loops 12 and 13 are then slipped endwise 95 between the sills 10 and into the guide-ways 20^a until the abutment portion 21 is substantially even with the abutments 20 on the members 11. The followers 14, retaining member 15^a and springs 15 are then assembled 100 in their proper relative position and when thus assembled are inserted in position within the loops 12 and 13 from beneath. After these parts 14, 15 and 15^a have been placed in position the tie-plate 17 is then 105 put in place to hold the springs and followers within the loops 12 and 13 and the tie-plate is secured to the sills by inserting the bolts 33. The walls of the channels 20^a will 110 prevent the loops 12 and 13 from separating.

from each other and will thus prevent the T-shaped head 31 of the draw bar from becoming disengaged and these walls also guide the loops 12 and 13 in their movement.

5 The operation of my improved draft rigging is as follows: If forces are exerted which tend to move the coupling head 30 away from the draft sills 10, the T-shaped head 31 will exert a force on the abutment 10 23 which will be transmitted to that follower 14 which is farthest from the draw bar through the side bar 22 and abutment portion 21. This will cause a force to be exerted on the other follower 14 through 15 the springs 15, which force will be transmitted to the sills 10 through the abutments 19 of the members 11. If forces are exerted which tend to jam cars together the T-shaped head 31 will exert a pressure on the 20 follower 14 with which it engages which will be transmitted through the springs 15 to the other follower 14 and through the abutments 20 of the members 11 to the sills 10.

25 It will be seen that I have provided a draft rigging which comprises few parts, which can be very easily assembled and which is of very rugged construction.

While I have shown and described a 30 specific form of shock absorbing mechanism between the followers 14 it is obvious that any suitable form of shock absorbing mechanism may be used.

Having thus described my invention what 35 I claim as new and desire to secure by Letters Patent is:—

1. The combination with a draw bar having a coupling head and a T-shaped head integral with said draw bar, the arms of 40 said T-shaped head extending substantially vertically, a pair of substantially parallel draft sills spaced from each other horizontally, and yielding compressible shock absorbing means, of means for connecting said 45 draw bar to said shock absorbing means comprising a pair of loops located in the space between said sills embracing said shock absorbing means, one loop embracing one arm of the T-shaped head, and the 50 other loop embracing the other arm, and means for holding said loops in position with respect to said T-shaped head supported by said sills.

2. The combination with a draw bar having a coupling head and a T-shaped head integral with said draw bar, the arms of 55 said T-shaped head extending substantially vertically, a pair of substantially parallel draft sills spaced from each other horizon-

tally, and yielding compressible shock absorbing means, of means for connecting said draw bar to said shock absorbing means comprising a pair of loops located in the space between said sills embracing said shock absorbing means, one loop embracing 60 one arm of the T-shaped head, and the other loop embracing the other arm, and means for holding said loops in position with respect to said T-shaped head and guiding them in their movement supported by said 65 sills.

3. The combination with a draw bar having a coupling head and a T-shaped head integral with said draw bar, the arms of 70 said T-shaped head extending substantially vertically, a pair of substantially parallel draft sills spaced from each other horizontally, and yielding compressible shock absorbing means, of means for connecting said draw bar to said shock absorbing means 75 comprising a pair of loops located in the space between said sills embracing said shock absorbing means, one loop embracing one arm of the T-shaped head, and the other loop embracing the other arm, and means for holding said loops in position with respect to said T-shaped head and guiding them in their movement supported by said 80 sills, said guiding means and loops being constructed so that in assembling the loops 85 may be put in place with respect to said guiding means by longitudinal movement with respect to said sills.

4. The combination with a draw bar having a coupling head and a T-shaped head 90 integral with said draw bar, the arms of said T-shaped head extending substantially vertically, a pair of substantially parallel draft sills spaced from each other horizontally, and yielding compressible shock absorbing means, of means for connecting said 95 draw bar to said shock absorbing means comprising a pair of loops located in the space between said sills embracing said shock absorbing means, one loop embracing one arm of the T-shaped head, and the other loop embracing the other arm, and means for holding said loops in position with respect to said T-shaped head.

5. A horizontal yoke for railway, draft 100 rigging comprising two loop-shaped members, each of said members having a transverse shoulder adapted to engage one of the shoulders of a draw bar butt.

In witness whereof, I have hereunto subscribed my name.

ALFRED COPON.
